UNITED STATES PATENT OFFICE

147,532

DESIGN FOR A FENDER

Robert Cadwallader, Detroit, Mich., assignor to
Chrysler Corporation, Highland Park, Mich., a
corporation of Delaware

Application February 6, 1946, Serial No. 126,294

Term of patent 7 years

(Cl. D14—6)

To all whom it may concern:

Be it known that I, Robert Cadwallader, a citizen of the United States, residing in the city of Detroit, county of Wayne, and State of Michigan, have invented a new, original, and ornamental Design for a Fender, of which the following is a specification, reference being had to the accompanying drawing, forming part thereof, in which:

Fig. 1 is a top plan view of the fender showing my new design;

Fig. 2 is a side elevational view thereof;

Fig. 3 is a front elevational view of the same; and

Fig. 4 is a rear elevational view thereof.

The dominant feature of my design resides in the specific contour of the wheel cut-out and its relation to and association with the contour of the upper portion of the fender. The dotted line

showing in Fig. 2 of the drawing is for illustrative purposes only.

I claim:

The ornamental design for a fender, substantially as shown and described.

ROBERT CADWALLADER.
